UNITED STATES PATENT OFFICE

NILS LUDVIG HAMMARSTRÖM, OF STOCKHOLM, AND ERIK ADOLF HOVING, OF KUNGSOR, SWEDEN, ASSIGNEES TO AKTIEBOLAGET MASKINFABRIKEN GOT, OF STOCKHOLM, SWEDEN, A CORPORATION

MECHANICAL MOVEMENT

Application filed December 9, 1926, Serial No. 153,657, and in Sweden November 19, 1925.

The present invention for which we filed an application for patent in Sweden Nov. 14, 1925, has for its object to provide means, with the aid of which motion may be transmitted 5 from a reciprocating part such as a piston rod alternately to two or more other movable parts.

The invention is principally distinguished by the fact that the reciprocating part, from 10 which the motion is derived, has a carrier adjustably connected therewith, abutments being provided in the path of said carrier in such a manner that the carrier, when moved, is actuated by the abutment or abutments and 15 is thus adjusted so as to hit the one or the other of the parts to which the motion is to be transmitted, the part in question being thus carried by the carrier.

The parts to which the motion is to be 20 transmitted are preferably connected with one another in pairs in such a manner that, when the one part is carried in the one direction, the other part is actuated by the same for movement in the opposite direction.

25 The device is suitable for different purposes, particularly for liquid meters having double measuring vessels one of which is to be filled with the aid of a pump while the other is at the same time to be emptied, the 30 supply to the one vessel and the discharge from the other being alternately opened and closed. This is effected in the most simple manner with the aid of an adjustable cock-plug, by which the two parts alternately receiving the motion are connected, while the 35 part provided with the carrier, from which the motion is derived, is directly connected with or forms the piston rod of the pump.

The accompanying drawings disclose an 40 embodiment of the invention as applied to a liquid meter.

Fig. 1 shows the device viewed in a front view, the carrier being in the one extreme position, and the adjustable cock being shown 45 in section, where it communicates with the inlets of the measuring vessels.

Fig. 1a is a section of the cock, where it communicates with the outlets of the measuring vessels.

50 Fig. 2 is a view of the device, wherein the

carrier is in the opposite extreme position and is pressed against the abutment.

Fig. 3 shows the same as Fig. 1, the carrier actuating another of the parts receiving motion.

Fig. 3a shows the same as Fig. 1, the cock plug being in another position.

Fig. 4 shows the device viewed from the side.

Fig. 5 is a front view of the device, the 60 carrier being in a middle position.

Fig. 5a shows the same as Figs. 1a and 3a, the cock plug being in an entirely closed position.

Referring now, more particularly to the drawing, there is provided a reciprocating member in the form of a rod 1 guided in guide bars 2, said rod being connected with or forming for instance the piston rod of a pump. 3 and 4 are two slidable members in the form of reciprocating rods guided in the guide bars 2, to which rods movement is to be transmitted alternately from rod 1. For this purpose the latter rod is provided with the double-armed carrier 5 which is mounted to 70 oscillate to and fro about a pin 6 attached in rod 1. The carrier is retained in different angular positions, either by friction or by means of a suitable locking member. Rods 3 and 4 are connected, through a cord or chain 7 extending over a pulley 8 which is attached to the spindle 9 of a cock plug 10. Rods 3 and 4 are provided with lugs 11 and 12 respectively projecting into the path of the arms of the carrier 5. In their extreme positions said 80 arms are stopped by a stop member 13 attached to the rod 1. A projection 14 on the carrier cooperates with a rigid abutment which, according to Fig. 2 consists of the upper guide bar 2.

The device operates in the following manner.

It is assumed, that the parts have such a starting position that the carrier 5 is pressed against the upper guide bar or abutment 2 95 and is thus turned into a middle position, that is to say a non-oblique position. If the rod 1 is then moving downwards, the one arm of the carrier hits that lug 11 or 12 on rods 3 and 4 which for the time being is in the high- 100

est position. According to Fig. 1, this lug is abutment 12 on rod 4. When the carrier struck the lug with its one arm, the carrier was turned by reason of the resistance and was brought into an oblique position, so that, on the continued downward movement of the carrier, the other arm of the latter moved freely past the lug 11 on rod 3. Rod 4 was then carried downwards, while rod 3 was pulled upwards actuated by the cord 7. The result of these movements is disclosed in Fig. 1. When the rod 1 again moves upwards, together with the carrier 5, the obliquely set carrier will still move freely past the lug 11 of rod 3, and the projection 14 of the carrier is finally pressed against abutment or guide bar 2, whereby the carrier is turned into the normal position according to Fig. 2. When rod 1 and the carrier again move downwards, the carrier 5 hits the lug 11 of rod 3, which abutment is then in the highest position. The carrier is adjusted owing to the resistance and is brought into an oblique position, so that its continued downward movement is not hindered by the lug 12 on rod 4. The latter is pulled upwards, when rod 3 is carried downwards by the carrier. The ultimate result of these movements is disclosed in Fig. 3. In this way the rod 1 will, with the aid of the adjustable carrier, transmit movement alternately to rods 3 and 4.

When the invention is applied to a liquid meter of the type set forth and is provided with an adjustable cock device, it is assumed, according to the drawing, that rod 1 is connected with or forms the piston rod of the pump, and that the rotatable pulley 8 is attached to the spindle 9 of the cock plug. If 15 designates the inlet of the cock, 16 and 17 the inlets thereof to the measuring vessels, and 18 and 19 the outlets of the cock from the measuring vessel, then the measuring is effected as follows. When the piston 1 moves upwards from the position according to Fig. 1, an amount of liquid will be forced in through the inlet 15, said liquid moving further through the inlet 16 to the one measuring vessel, while an amount of liquid escapes at the same time through outlet 19 (Fig. 1a) from the other measuring vessel. When the piston rod 1 then moves downwards and carries the rod 3 along with it, after the carrier has been adjusted against the abutment or guide bar 2 as hereinbefore described, the cock plug 10 will be adjusted into the position according to Fig. 3 or 3a respectively. When the piston rod moves back upwards, that is to say when it makes its pump stroke, an amount of liquid is forced in through the inlet 15, and moves further through the inlet 17 to the emptied measuring vessel, while the measuring vessel filled on the previous pump stroke is simultaneously emptied through outlet 18. The inlets and outlets of the li-

uid meter are thus adjusted alternately on each successive pump stroke.

The amount of liquid forced into the measuring vessel in question on each pump stroke will be dependent on the length of the pump stroke. The arrangement in question makes it possible in a simple manner to alter the quantity which is thus to be measured. If the carrier 5 is permitted to move freely between the guide bars 2, one of which forms the abutment for the adjustment of the carrier, a certain maximum quantity will be measured. If the movement of the carrier or the pump stroke respectively is shortened, the quantity will be less, and this is effected in a simple manner by a displacement of the abutment of the carrier. If the abutment is displaced into a position right between the guides 2, which can take place, according to the drawing, by inserting an additional abutment 20 in the said place, the pump rod 1 can move only half the way, and the measured quantity will be half as large as before. In this way the abutment can be displaced to any point desired, according as a larger or smaller quantity of liquid is to be measured.

The arrangement ensures that the meter cannot be adjusted so as to effect wrong measurements. It is conceivable that the carrier may be manually adjusted so as to actuate the two rods 3 and 4 simultaneously in a middle position, as shown in Fig. 5. If this takes place, all channels of the cock will be closed, as will appear from the drawing, and when the pump rod is again to be moved upwards, together with the carrier, in order to effect pumping, this is rendered impossible, in that the cock does not permit passage of liquid in any place. Consequently, the pump rod will be completely locked. Pumping cannot, therefore, take place if the carrier is not first brought into such a position as to actuate the rods in the normal way.

What we claim is:—

1. In a device for the transmission of movement, a reciprocating member, a pair of slidable members adapted to be moved alternately in opposite directions, a carrier mounted for oscillation on the reciprocating member, a projection on the carrier, lugs on said slidable members positioned in the path of movement and engageable by the carrier, and an abutment coacting with the projection on the carrier and adapted after engagement of the carrier with either of the lugs to shift said carrier to normal position.

2. An arrangement as claimed in claim 1, wherein a rotary member is provided, and a flexible element trained about the rotary member and connected with the slidable members so that when one member when moving in the one direction will actuate the other so that it will in turn move in the opposite direction and incidentally impart alternate rotation to said rotary member.

3. An arrangement as claimed in claim 1, wherein the carrier is double armed and provided with abutting surfaces, and an abutment is mounted on the supporting point of the carrier and provided with a straight edge forming a stop which coacts with the abutting surfaces on the carrier so as to determine the position which the carrier occupies after it has moved against said straight edge.

10 4. An arrangement as claimed in claim 1, wherein upper and lower guide bars are provided to guide the reciprocating and sliding members, and the upper guide bar forming the abutment which coacts with the projection on the carrier, substantially as and for the purposes set forth.

In testimony whereof we affix our signatures.
